UNITED STATES PATENT OFFICE.

GOTTLIEB BRIEGEL, OF FOND DU LAC, WISCONSIN.

PNEUMATIC TOOL.

1,105,876.

Specification of Letters Patent. Patented Aug. 4, 1914.

Application filed November 7, 1913. Serial No. 799,671.

To all whom it may concern:

Be it known that I, GOTTLIEB BRIEGEL, a citizen of the United States, residing at Fond du Lac, in the county of Fond du Lac and State of Wisconsin, have invented 5 certain new and useful Improvements in Pneumatic Tools, of which the following is a specification.

This invention relates to the class of 10 pneumatic implements that comprises a reciprocating piston acting upon a rivet set or other tool for transmitting the blows of the piston to the article operated upon, and refers particularly to means for preventing 15 the piston from being discharged from the barrel of the implement.

In pneumatic implements wherein the shank of the tool is of smaller diameter than the piston, the piston cannot, of course, be discharged through the bore in which the tool shank is slidably mounted; but in the case of implements wherein the shank of the tool is of larger diameter than the piston (as in pneumatic riveters and other powerful pneumatic implements) no means has ever been provided to prevent the piston from flying out of the front end of the barrel when the tool is not held against the work. To keep the rivet set or other tool from dropping out of the implement when the latter is not in use, a spring clip or other detachable, yieldable connection is employed between the implement and the tool, but such clip or the like is not sufficient to 35 prevent the piston from being discharged from the implement in case the throttle valve of the implement is accidentally or maliciously opened at a time when the tool is not in contact with the rivet or other part 40 being acted upon. Much damage and numerous fatal injuries have been caused in the past by the lack of means for preventing discharge of the pistons of pneumatic riveters and similar powerful implements.

45 This invention contemplates the provision of effective and durable means for preventing such discharge.

In the accompanying drawings, Figure 1 is a side elevation, partly in section, of a 50 pneumatic riveter embodying the features of my invention, showing the implement applied to the work *a*. Fig. 2 is a fragmental sectional view to show how the piston is restrained when the implement is removed 55 from the work. Fig. 3 is a fragmental view of an alternative construction.

While the invention may be applied to various forms of pneumatic reciprocating-piston implements, I have illustrated in the drawings a pneumatic riveter of common 60 form comprising a barrel or cylinder 1, a handle 2, and a throttle lever 3.

4 is a piston, and 5 is the rivet set. The latter consists of a head 5^a and a cylindrical shank 5^b, said shank being slidably mounted 65 in a bore 6 in the forward end of the implement. The rivet set is prevented from falling out of the bore 6 by a spring clip 7 in the form of a split ring or band that embraces the shank 5^b of the rivet set and lies 70 loosely within an annular internal groove 8 in the implement. The spring clip 7 grips the rivet set hard enough to prevent the rivet set from dropping out of the bore 6, while permitting the rivet set to move 75 in said bore under the impact of the piston. The clip is very simple in construction, and, being inclosed, is protected from injury.

The bore 9 in which the piston is arranged to reciprocate is of less diameter than the 80 bore 6. The forward portion 10 of the bore 9 is enlarged as usual, for the reception of the compressed air. At the juncture of the bores 6 and 9, the bore 9 is tapered inwardly 85 to form a conical or annular tapered wall 11, and the forward portion 12 of the piston 4 is correspondingly tapered. The taper of the parts 11 and 12 may be straight, as shown in Figs. 1 and 2, or curved, as indicated in Fig. 3.

90 13 is the reduced forward end of the piston, said reduced portion being of sufficient length to allow the piston to strike the tool, in the normal use of the implement, without bringing the surface 12 into contact with 95 the wall 11.

In the event that the throttle lever 3 should be operated at a time when the rivet set is not in contact with the work, the piston 4 will be prevented from shooting out 100 of the implement by the engagement of the tapered portion 12 of the piston with the correspondingly tapered wall 11 of the cylinder. The wall 11 is of such ample size 105 as to present a large area of resistance to the powerful impact of the piston, and thus will not be battered or sheared out.

I claim as my invention:

1. A pneumatic implement comprising a 110 barrel, a tool slidably mounted in the forward end of the barrel, and a reciprocating piston in the barrel arranged to strike the

tool, the barrel and the piston having correspondingly tapered surfaces coacting to prevent the piston from being discharged from the barrel.

5. 2. A pneumatic implement comprising a barrel having a forward and a rear bore, said bores communicating with each other, a tool slidably mounted in the forward bore, and a piston mounted in the rear bore, the forward end of the rear bore being tapered inwardly, and the forward portion of the piston being correspondingly tapered, the tapered portion of the rear bore serving to prevent the piston from being discharged
10 15 from the barrel.
3. A pneumatic implement comprising a barrel having a forward and a rear bore, said bores communicating with each other,

a tool having a shank slidably mounted in the forward bore, a piston slidably mounted in the rear bore, said piston being of less diameter than the shank of the tool, the forward end portion of the piston being of less diameter than the body of the piston, said forward end portion being connected to the 25 piston body by an annular tapered portion, the forward end of the rear bore being correspondingly tapered to prevent the piston from being discharged from the barrel.

In testimony whereof I affix my signature 30 in presence of two witnesses.

GOTTLIEB BRIEGEL
